DESIGN FOR A COMBINATION TOASTER AND COOKER

Otto E. Stelzer, German Township, St. Joseph County, Ind.

Application January 5, 1945, Serial No. 117,287

Term of patent 14 years

(Cl. D81—10)

To all whom it may concern:

Be it known that I, Otto E. Stelzer, a citizen of the United States, residing in German Township, in the county of St. Joseph, State of Indiana, have invented a new and original Design for a Combination Toaster and Cooker, of which the following is a specification, reference being had to the accompanying drawing, forming part thereof.

The figure is a perspective view showing the top, front and one side of a combination toaster and cooker embodying my new design. The left side of the device is like the right side shown, and the back is substantially plain.

I claim:

The ornamental design for a combination toaster and cooker, as shown and described.

OTTO E. STELZER.
